UNITED STATES PATENT OFFICE

161,548

CONTAINER FOR ROSARY BEADS

Henry J. Smoleroft, New York, N. Y.

Application April 8, 1950, Serial No. 9,067

Term of patent 3½ years

(Cl. D58—12)

To all whom it may concern:

Be it known that I, Henry J. Smoleroft, a citizen of the United States, residing at city of New York, county of Bronx, State of New York, have invented a new original, and ornamental Design for a Container for Rosary Beads, of which the following is a specification, reference being had to the accompanying drawing, forming a part hereof.

In the drawing:

Fig. 1 is a front elevational view of a container for Rosary Beads, showing my new design;

Fig. 2 is a rear elevational view thereof;

Fig. 3 is a side elevational view; and

Fig. 4 is a perspective view showing the container in open position.

I claim:

The ornamental design for a container for rosary beads, as shown.

HENRY J. SMOLEROFF.
